UNITED STATES PATENT OFFICE.

ERNEST A. FRARY AND EDWARD N. FRARY, OF DEERFIELD,
MASSACHUSETTS.

GAS-LIGHTING APPARATUS.

No. 849,116.

Specification of Letters Patent.

Patented April 2, 1907.

Application filed March 9, 1906. Serial No. 306,178.

To all whom it may concern:

Be it known that we, ERNEST A. FRARY and EDWARD N. FRARY, citizens of the United States of America, and residents of

5 Deerfield, in the county of Franklin and State of Massachusetts, have invented certain new and useful Improvements in Gas-Lighting Apparatuses, of which the following is a full, clear, and exact description.

10 This invention relates to an improved apparatus for gas-lighting of a kind which comprises automatic means controlled by the pressure of the gas at the gasometer or at or near the source of gas-supply for causing the 15 turning on of the gas to the individual burners or any number of street or other burners and for the ignition of the turned-on gas and also for the shutting off of the gas at all or any number of the burners when desired for 20 the extinguishing of all of the lights, advantage being taken by provisions at the gasometer, and also by provisions individual to the proper burners, of the illuminating-gas to be supplied at the burners to constitute the 25 fluid-pressure means for effecting the turning on and lighting of the gas and the shutting off of the gas and extinguishing of the lights.

Within the capabilities of this invention 30 gas-burners in houses may be supplied, as usual, from the common source of gas-supply, which need not necessarily have electric turning on and lighting devices, and street-light burners also supplied from such source, 35 it still being possible at the gas-making plant to cause the lighting and thereafter the shutting off of the street-lights without materially interfering with the conditions for illumination by the house-burners at any 40 time.

The invention consists in the constructions, arrangements, and combinations of parts, as hereinafter described in conjunction with the accompanying drawings and as set 45 forth in the claims.

In the drawings, Figure 1 is a view in elevation and having the nature of a diagram, showing the general arrangements and availability of the device. Fig. 2 is a sectional 50 elevation, on a larger scale, of the burner supported by a street-lamp post and having burner opening and shut-off devices and lighting devices therefor. Fig. 3 is a hori-

zontal sectional and plan view of the parts as seen below the line 3 3, Fig. 2.

55

Similar characters of reference indicate corresponding parts in all of the views.

In the drawings, A represents a gas-supply tank, closed reservoir, or gasometer having a vertically-movable section a, which may rise 60 and lower according to the pressure of the gas therein and which may have regulating means for reducing or increasing the pressure in such reservoir or gasometer.

B represents a pipe for conveying the 65 manufactured acetylene or other gas from the gas-machine by way of an upstanding branch B' into said gasometer, and B² represents the distributing-pipe leading from communication with the gasometer, which it has by 70 way of said upstanding branch B', said pipe B² being understood as extended underground throughout a town or city and having connections by upright branches C, only one of which is shown in Fig. 1, to diaphragm-cases D, which by the depending threaded hub b of each are screw-connected with the upper ends of the pipes, vertically extending through the respective lamp-posts.

75 Each diaphragm-case, as shown in Figs. 1 80 and 2, comprises a lower section 10 of cup shape, at the central portion of which the aforementioned screw-connection hub is provided, and surrounding the flanged top of the cup-shaped section 10 is the flexible dia- 85 phragm d, which is clamped thereto by the upper section 12 of the diaphragm-case, which comprises the clamping-ring 13, through which the confining-screws 14 pass downwardly through the marginal portion of 90 the diaphragm and the flanged portion of the lower section 10, and said upper section furthermore comprises upright portions 15 16 and the uniting horizontal cross-bar 17.

95 The duct 18 leads laterally and upwardly through the side wall of the casing-section 10 and matches with the duct or passage 19, which leads not only vertically through the upright portion 16 of the casing-section 12, but for a suitable distance horizontally 100 through the horizontal cross-bar 17 and upwardly through the upstanding round boss 20, which is formed as an integral part of the horizontal bar 17.

105 The gas-burner F, comprising a central tubular body, is screw-connected to the afore-

- said upstanding boss 20, and this burner may be any of a variety of well-known forms of automatic gas-lighting burners which have means for the production of an electric spark 5 simultaneously with the operation of opening the gas valve or cock, which is provided for opening and closing the passage through the burner, and which passage leads to the burner-tip.
- 10 Suitably adjacent the upstanding boss 20 and to one side thereof the cross-bar 17 of the upper section of the diaphragm-case is constructed with a hole 22 vertically therethrough, in which is fitted and supported a 15 tubular section 23, of fiber, rubber, or other insulating material, and on the externally-screw-threaded depending portion of this sleeve 23 a circular thumb-nut 24 screw-engages and has between the flanged head of 20 such nut and the diaphragm d the light spiral diaphragm-regulating spring f , and 25 represents a check or locking nut screwing on the threaded insulating tubular section 23, adapted to be set against and confine in any given adjustment the spring-adjusting nut 24.
- 25 g represents a circuit-closing rod or stem, which is guided for vertical movement through the insulating depending member g , its lower end resting on or being connected with the diaphragm, and its upper end, which is here shown as provided with the widened head 25, has its location between the contact-lugs 26 and 27, which are carried by the separated upper and lower 30 clamping-collars 28 and 29, which have adjustable and constrictive engagements about the insulation-sleeve 30, which encircles the upstanding boss 20 of the diaphragm-casing section 17.
- 35 32 represents the spindle or stem of a plug-valve, which is understood as rotatable in and across the gas-passage 33, which leads vertically through the body of the burner to the burner-tip. This valve-stem 32 has 40 a disk 34, carrying an eccentrically-located pin 35, said disk having limited back and forth partial rotary movements.
- 45 H represent electromagnets at opposite sides of the central body of the gas-burner, and i represent the armatures therefor, both connected at the common pivot 37 and having each a lever-arm 38.
- 50 j represents a local battery for the post-supported burner, and the wire 40 in connection therewith is grounded at g in the lamp-post, and the wire 42 is connected with the metallic sleeve 43 in metallic connection with the rod G , which plays vertically therewithin, and which sleeve is tightly fitted in 55 the aforesaid depending tubular member 23 of insulating material.
- The wire 44 has connection with the contact-lug 26 and runs therefrom to one of the electromagnets H , and the wire 44^a connects 60 the electromagnet with the body of the

burner, which is in metallic contact with the diaphragm-case.

The wire 45 connects the other contact-lug 27 with the other electromagnet h , and the wire 45^a connects the electromagnet with the metallic body of the burner, which is in connection with the diaphragm-case.

m represents the sparking device adjacent the burner-tip, which is made active by the current for the electromagnet-circuits, as 75 common in this well-known class of electric gas-lighting devices, it being expressly stated that this invention comprises no novelty in the electric-lighting gas-burner and that any one of a variety of well-known kinds of electric gas-lighting burners may be used in carrying out this invention.

For operation, early in the evening, for instance, when all of the gas-burners in the system are to be lighted, the pressure in the 85 gasometer is raised above the normal, (it being understood that the normal pressure is one which will maintain the diaphragm d in the position intermediate of the limits of its deflections, so that the head 25 of the stem g 90 will be more or less nearly midway between the contact-lugs 26 and 27,) such raising of the pressure above the normal causing the upward distention of the diaphragm and the lifting of the rod g , so that the head 25 of the 95 circuit-closing rod G by coming to bearing against the contact-lug will establish a circuit from the battery j , wire 42, and metallic sleeve to and through the rod G , having a sliding contact with said sleeve to and 100 through wire 44, one of the electromagnets H , and return connection 44^a to the metallic body of the burner, near which the wire 40 from the other pole of the battery is grounded. The establishment of this circuit energizes 105 one of the electromagnets H and insures by the motion of the armature and armature-lever arm the partial rotary motion of the pin-provided disk on the gas-cock, opening the latter concurrently with which 110 the ignition device m becomes live for the ignition of the gas, which is now permitted to be delivered through the gas-burner. The time arriving when the gas-lights of the system should be extinguished, the pressure in 115 the gasometer is lowered by some means, whereupon the diaphragm, which has remained subject to the pressure of the gas which passes through the diaphragm-chamber, becomes so lowered and overpowered by 120 the pressure of the diaphragm-spring f as to permit the head 25 of the circuit-closing rod to be brought to bearing against the lower contact-lug 27, thereby establishing a circuit 125 through the other electromagnet, which results, through the movement of its armature and lever-arm, in the reversing of the motion of the gas-cock, shutting off the gas through the burner, and putting out the light.

It is deemed desirable after the gas-cock 130

has been opened through the fluid-pressure and electromagnet means described and the issuing gas ignited to slightly reduce the pressure at the gasometer, not enough, however, to cause the reversed action of the mechanism, but sufficiently to carry the head of the circuit-closing rod G to its position between and out of contact with either of the contact-lugs, thereby, leaving all circuits 10 opened and without wasting the energy of the battery.

The provision of the diaphragm-spring *f* and the adjustable means for varying the compression of such spring, whereby the resistance of the diaphragm opposed to the gas-pressure under the diaphragm may be regulated, insures that each of the apparatuses comprising the diaphragm in the entire system may be rendered capable of the expected actions controllable by any adopted pressure in the gasometer.

Variations of the pressure in the tank or gasometer, having the movable chamber-expanding portion *a*, to such extremes as to 15 by the maximum distend the diaphragm *d* of the lamp-post burners at the moment of the lighting of the same by the intermediate pressure for normal conditions during the lighting period, and by the most greatly reduced pressure, to permit the collapse of each diaphragm for the extinguishings of the lights, may be obtained by a person manually placing first a maximum weight on the movable portion *a* of the gasometer, leaving it 20 thereon for but one or a very few minutes, then reducing such weight in some degree, and finally removing the weight, the regulation of the pressure being moreover further manually controllable by the valve 55 in the gas- 25 supply pipe B; but the apparatus is rendered much more complete and satisfactory when made inclusive of apparatus for automatically lowering the pressure in the gasometer to the minimum at the predetermined 30 time when the lights at the lamp-post burners are to be extinguished, and for almost immediately thereafter automatically restoring the pressure to its normal degree, whereby the local batteries adjacent the lamp-post 35 will not be run down, but also whereby other burners which may be pipe-connected in the system—as, for instance, in houses—may be supplied with the gas at normal pressure and available at substantially all times desired 40 for illumination, and to these ends a weighted lever 51 is link-connected to the body of the gas-supply-pipe valve 51 and has a stud-and-slot engagement with the stem of such valve.

45 A detent 54 is pivotally mounted on a support at the side of the gasometer and adapted, as shown by full lines in the drawings, to engage and hold in its lowered position the movable gasometer-section *a*.

53 represents a pivoted detent for holding 65 the catch 44 in its engaging position. A flexible connection 49 connects the catch and the valve-operating lever 51.

50 represents a clockworks, which may be of any of the alarm-clock types, to be set for 70 liberating at a predetermined time a self-rotating arbor which may carry a cam to operate against and move a bar which has a connection 52 with the detent 53.

*a*² represents a weight above the movable 75 gasometer-section *a*, the same being suspended by a cord or other flexible connection 65, which is sheave-guided at 66 and 67 and has winding engagement around an overhead spool supported horizontally for rotation in 80 journal-bearings 68 and provided with a ratchet or toothed wheel 69, with which a detent 63 normally engages.

60 represents a second clockworks of the same character as the one 50 above referred 85 to and employed to be set to liberate a self-rotating arbor thereof a minute or very soon after the operation of the clockworks 50 to cause a draft on the flexible connection 62, which is fastened to the detent 63, and the 90 disengagement of the latter from the toothed wheel 69.

An additional flexible connection 70 is secured to the weight *a*² and to the valve-operating lever 51, being intermediately 95 suitably sheave-guided, as seen at 72.

Now, in operation at the moment when the street-lamps are to be extinguished the automatic portion of the clockworks 50 having been properly set therefor the detent 53 100 will be withdrawn from the catch 54, which will release the movable gasometer-section *a* to rise, enlarging the space within the tank and lowering the pressure, such pressure lowering being most promptly and certainly as 105 assured because immediately the catch 54 is moved to release tank portion *a* the weighted valve-lever being then unrestrained swings downwardly and closes the gas-supply-pipe valve. The lowering of the pressure causes 110 the complete lowering of the diaphragms *d* establishing the circuits in the electromagnetic devices for the post-lights, which are operative to close the gas-cocks. Almost immediately following this action the second 115 clockworks 60 causes the releasing of the detent 63, whereupon the weight *a*² is free to descend, imposing its force against the movable gasometer-section *a* sufficiently to restore the pressure to the normal, it being noted 120 that the descending weight through the flexible connection 70 upwardly swings the valve-operating lever, again opening the valve in the pipe supplying gas into the gasometer.

In order that the weight may not fall with 125 too much violence on the upper tank-section, a counterweight 75, but less heavy than the weight *a*², is suspended by a cord or chain 76,

having a winding engagement about the spool 64 in the reverse-direction from that of the cord 65.

The maximum pressure in the gasometer 5 may be established and momentarily maintained by additional weights manually applied on the top of the tank-section *a* at the proper time early in the evening and when it is convenient for an attendant to do so, or 10 other pressure-establishing means, forming no part of this invention, may be employed.

We claim—

1. An electric-lighting gas-burner having a cock controlling the gas-delivery thereto 15 and comprising a gas-ignition device, and a gas-pipe for supplying gas through said burners, electromagnetic devices for opening and closing the gas-cock and operating the ignition device, and comprising two contacts and 20 a circuit-closing movable member therebetween, a casing connected with the pipe and burner and having a diaphragm in unison with which said circuit-closing member moves, a spring for imposing a resistance 25 against the movement of said diaphragm in one direction, and means for varying the tension of said spring, a gas-tank connected with said diaphragm-casing and with the gas-passage through said burner, and means for varying the gas-pressure in said tank.

2. An electric-lighting gas-burner having a cock controlling the gas-delivery therethrough and comprising a gas-ignition device, electromagnetic devices for opening 35 and closing the gas-cock and energizing the ignition device, and comprising two contacts and a circuit-closing movable member therebetween, a casing having a diaphragm, in unison with which said circuit-closing member moves, a gas-tank having a movable portion, a gas-supply pipe connected therewith and with which tank a supply-pipe has connection and with which said diaphragm also 40 has communication, automatic means for lowering, below its normal, the pressure in 45 said gas-tank and against the diaphragm, and automatic means for thereafter increasing the gas-pressure in said tank.

3. A gas-burner having a gas-cock and an 50 ignition member, electromagnetic means for closing and opening the gas-cock and comprising a movable circuit-closing member, a casing provided with a diaphragm coacting with said circuit-closing member, and a gas- 55 tank having communication with said diaphragm-casing, clockworks-actuated means for automatically lowering the gas-pressure in said tank, and clockworks-actuated means for again increasing the gas-pressure in said 60 tank, for the purposes set forth.

4. In an automatic gas-lighting apparatus, the combination with a burner, a gas-conduit connected therewith, and a cock controlling the 65 passage of gas through the burner, of electromagnetic mechanism comprising a mag-

net, and armature operable on the gas-cock to open, and a magnet and armature operable on the gas-cock to close it, and an electric gas-lighter coacting with one of said electromagnets, normally open circuit-conductors having connected therewith a battery and in connection with said electromagnets and also connected with separated contacts, a diaphragm subject to the pressure of the gas passing through said conduit to the 75 burner, and a circuit-closing contact-piece controlled by the diaphragm and movable against either of said contacts according as the gas-pressure is raised or lowered, and for establishing circuits through said electromagnets for operating said gas-cock in either direction.

5. In an automatic gas-lighting apparatus the combination, with a gas-lighting burner having a cock adapted to control the gas- 85 passage therethrough, electromagnetic devices operative to open and close said cock and a diaphragm operative to control said electromagnetic cock-operating devices, of a gas-tank having a movable portion and in 90 communication with a gas-supplying pipe and with a conduit or branch pipe connected with the gas-burner, a catch for restraining in a lowered position the movable portion of the gas-tank, a detent for said catch, and a 95 clockworks coacting with said detent and operable at a predetermined time to free the detent from the catch whereby the movable portion of the tank may have a rising movement to cause a lowering of the gas-pressure 100 therein, and for effect on said diaphragm.

6. In an automatic gas-lighting apparatus the combination, with a gas-lighting burner having a cock adapted to control the gas- 105 passage therethrough, electromagnetic devices operative to open and close said cock and a diaphragm operative to control said electromagnetic cock-operating devices, of a gas-tank having a movable portion and in communication with a gas-supplying pipe 110 and with a conduit or branch pipe connected with the gas-burner, a self-closing valve in the gas-supply pipe, means for restraining said valve in its open position, and a clock- 115 works coacting with said valve-restraining means and adapted for operation at a predetermined time to release said valve for a closing movement.

7. In an automatic gas-lighting apparatus the combination with a gas-lighting burner 120 having a cock adapted to control the gas- passage therethrough, electromagnetic devices operative to open and close said cock and a diaphragm operative to control said electromagnetic cock-operating devices, of a 125 gas-tank having a movable portion and in communication with a gas-supply pipe and with a conduit or branch pipe connected with the gas-burner, a valve in the gas-supply pipe having a weighted operating-lever there- 130

for, a catch for restraining in a lowered position the movable portion of the gas-tank, a 5 detent for said catch, a connection between said catch and said valve-operating lever, and a clockworks coacting with said detent and operable at a predetermined time to free such detent from the catch whereby the gas-supply-pipe valve may have a closing movement and whereby the movable tank portion 10 may have a rising movement under the gas-pressure therein.

8. In an automatic gas-lighting apparatus the combination with a gas-lighting burner having a cock adapted to control the gas- 15 passage therethrough, electromagnetic devices operative to open and close said cock and a diaphragm operative to control said electromagnetic cock-operating devices, of a gas-tank having a movable portion and in 20 communication with a gas-supply pipe and with a conduit or branch pipe connected with the gas-burner, a valve in the gas-supply pipe having a weighted operating-lever therefor, a catch for restraining in a lowered position 25 the movable portion of the gas-tank, a detent for said catch, a connection between said catch and said valve-operating lever, a clockworks coacting with said detent and operable at a predetermined time to free such 30 detent from the catch whereby the gas-supply-pipe valve may have a closing movement and whereby the movable tank portion may have a rising movement under the gas-pressure therein, a weight above the gas-tank 35 having a flexible suspension means therefor, means for holding said weight above and normally free from the movable portion of the tank comprising a detent therefor, and another clockworks coacting with said last- 40 named detent and operable at another predetermined time for liberating the suspended weight whereby it may exert its gravitational force against the movable portion of the gas-tank thereby increasing the already-lowered 45 gas-pressure therein.

9. In an automatic gas-lighting apparatus the combination with a gas-lighting burner having a cock adapted to control the gas- 50 passage therethrough, electromagnetic devices operative to open and close said cock and a diaphragm operative to control said electromagnetic cock-operating devices, of a gas-tank having a movable portion and in communication with a gas-supply pipe and with a conduit or branch pipe connected with the gas-burner, a valve in the gas-supply pipe having a weighted operating-lever therefor, a catch for restraining in a lowered position 55 the movable portion of the gas-tank, a detent for said catch, a connection between said catch and said valve-operating lever, a clockworks coacting with said detent and operable at a predetermined time to free such 60 detent from the catch whereby the gas-supply-pipe valve may have a closing movement and whereby the movable tank portion may have a rising movement under the gas-pressure therein, a weight above the gas-tank having a flexible suspension means therefor, means for holding said weight above and 65 normally free from the movable portion of the tank comprising a detent therefor, another clockworks coacting with said last-named detent and operable at another predetermined time for liberating the suspended 70 weight whereby it may exert its gravitational force against the movable portion of the gas-tank thereby increasing the already-lowered gas-pressure therein, and a connection between said weight and gas-supply-pipe-valve- 75 operating lever whereby on the descent of the weight such lever will be drawn upwardly and the valve again opened.
